United States Patent Office

Des. 190,158
Patented Apr. 25, 1961

190,158

TAP HANDLE

Todd Harris, Webster, N.Y., assignor to Bastian Brothers
Company, Rochester, N.Y.

Filed Nov. 17, 1960, Ser. No. 62,888

Term of patent 14 years

(Cl. D2—3)

Fig. 1 is a rear perspective view of a tap handle showing my new design;

Fig. 2 is a top plan view of the tap handle;

Fig. 3 is a front elevation of the tap handle; and

Fig. 4 is a side elevational view of the tap handle.

I claim:

The ornamental design for a tap handle, as shown.
